UNITED STATES PATENT OFFICE.

MATHIAS J. EWEN, JR., OF EVANSVILLE, INDIANA.

DESIGN FOR A GAME-BOARD.

56,420.

Specification for Design.

Patented Oct. 26, 1920.

Application filed April 30, 1920. Serial No. 378,026. Term of patent 7 years.

To all whom it may concern:

Be it known that I, MATHIAS J. EWEN, Jr., a citizen of the United States, residing at Evansville, county of Vanderburgh, State of Indiana, have invented a new, original, and ornamental Design for Game-Boards, of which the following is a specification, reference being had to the accompanying drawing, forming part thereof.

I claim:

The ornamental design for a game board, as shown.

In testimony whereof I affix my signature.

MATHIAS J. EWEN, JR.
